UNITED STATES PATENT OFFICE

CHARLES W. QUIMBY, OF PHILADELPHIA, PENNSYLVANIA, ASSIGNOR TO E. F. HOUGHTON AND COMPANY, OF PHILADELPHIA, PENNSYLVANIA, A CORPORATION OF PENNSYLVANIA

VALVE SEAT FOR GAS GOVERNORS AND THE LIKE

Application filed December 26, 1928. Serial No. 328,627.

My invention relates to a novel leather product and to the method of preparing the same, and more particularly it relates to a leather product impervious to the passage of fluids.

5 One object of my invention is to provide a leather product through which no gas or liquid can pass and which for this reason is capable of successful use for many purposes, such, for example, as seats on the valves of gas governors, regulators and the like.

10 A further object is to provide a leather product rendered impermeable to gas or liquid by a coating or covering tenaciously held thereon, which coating or covering is characterized by its high wear-resisting qualities and its ability to withstand the action of moisture and oils.

15 20 Still another object is to provide a leather product having the strength and pliability of leather but which, due to a novel treatment, has improved properties and a longer life.

25 A further object is to provide a simple and inexpensive method of preparing the product. Other objects will be apparent from a consideration of the specification and claims.

In the accompanying drawings, Figures 1 30 and 2 are enlarged perspective views of the valve seat for gas governors and the like with a section cut away.

The use of leather for some purposes where its properties of strength and pliability are 35 particularly desirable has not been successful because of the many minute pores in the leather through which fluids such as air or other gases pass. One particular instance of such use is found in the valve seats of gas governors or regulators where it is essential that the material for the seats be completely impervious to the passage of gas.

40 The leather product of the present invention is characterized by the presence of a coating of cellulose ester on at least one surface of the leather piece. This coating is tenaciously held on the leather and cannot be separated from it and it, therefore, may be considered as an integral part of the 45 leather product. The coating is unaffected

by moisture and oils and increases the wear-resisting qualities and the life of the leather product.

50 My invention contemplates a coating or covering on the leather comprising a cellulose ester by which term I include the various nitrocelluloses as well as cellulose acetate. These compounds, or solutions of them, are known under various names such as pyroxyline, collodion, and acetate ester. The coating may also include various other compounds carried by the essential cellulose ester, for example, camphor or various dyes and pigments.

55 In practicing the present invention, the coating or covering of cellulose ester may take the place of the grain side of the leather. The leather to be treated is leveled and the grain of the leather removed by any suitable means such as by splitting, buffing, or 60 slickering. The leather is then ready for the treatment which results in the coating of the cellulose ester and the resulting impermeability of the leather product to fluids. This cellulose ester may be applied in a variety of ways.

65 In a preferred example, the leather surface from which the grain has been removed is treated with an organic liquid or a mixture of such liquids in which the particular cellulose ester to be applied is soluble. For example, if a pyroxyline varnish or cement is to be applied, the leather may be wet with a mixture of acetone, butyl acetate and ethyl acetate, various proportions being applicable. 70 While the leather is still wet, the pyroxyline cement is applied. The leather, moist with the organic liquids in which the pyroxyline is soluble, absorbs the pyroxyline and the surface pores are filled with this material before 75 the solvents have evaporated. The leather is then subjected to pressure, the time varying from a few minutes to many hours depending upon the resultant leather product desired. This method of applying the cellulose ester insures a strong bond between the coating and the leather body and the two will 80 not separate in use even under severe conditions.

85 If desired, instead of pretreating the 100

leather with an organic liquid or a mixture of them, a relatively dilute solution of the pyroxylene or other cellulose ester may be applied to the surface of the leather from 5 which the grain has been removed, or to the flesh side of the leather. The dilute solution will penetrate the pores to a sufficient extent to preclude the possibility of separation of the coating in use. The leather thus treated 10 may then be subjected to pressure, or treated in any manner which will give a smooth, flexible surface to the product.

As an optional method of rendering the 15 leather impervious to the passage of fluids, a fibrous sheet of paper or cloth may be applied to the surface of the leather. A suitable organic cement or glue may be used to bind this fibrous sheet to the leather. For example, ordinary glue may be used. Obviously, also, the cellulose esters described hereinbefore may be used effectively. In the 20 presence of organic solvents, however, an organic binder which is insoluble in the solvent is preferred. The adhesive nature of the 25 binder before drying is relied upon to securely bind the fibrous material to the surface of the leather. The products made in this way are rendered impervious to fluids not only by the binder but also by the fibrous 30 sheet.

In the drawings, Figure 1 is a perspective view of a valve seat 1 with a section cut away, comprising a leather base 2 and a gas-impermeable coating of cellulose ester 3 tenaciously held thereon as shown at 4. Figure 2 is a 35 similar view, showing the optional construction comprising the leather base 2, and a fibrous sheet 5 securely bound on the leather base 2 by means of an organic binder shown 40 at 6.

For special purposes, it may be desirable to subject the leather product, after it has been rendered impervious, to further treatment. For example, the product may be 45 filled, according to well-known methods, with various oils and waxes.

The leather product by this invention has many applications. It is particularly useful for gas governors or regulators as the seats 50 on the intake valves. If the product is to be for this purpose, it is cut into the necessary sizes and shapes for use as seats on the valves. These treated leather pieces close the aperture tightly so that no gas can pass until 55 the regulating lever which holds the piece of leather over the intake aperture is raised, causing the release of the pressure on the leather and allowing the gas to pass by forcing the leather up. This raises the pressure 60 in the governor chamber and when sufficient pressure is reached, it automatically lowers the lever which forces the leather back onto the seat of the intake valve, thus closing it.

Considerable modification is possible in the 65 method of preparing the leather product of

this invention, as well as in the compounds used in the surface coating without departing from the essential features of the invention.

I claim:

1. A valve seat for gas governors and the like, which is impervious to the passage of gases, comprising a leather base and a gas-impermeable coating of cellulose ester tenaciously held thereon. 70

2. A valve seat for gas governors and the like, which is impervious to the passage of gases, comprising a leather base having a surface from which the grain has been removed, and a gas-impermeable coating of cellulose ester in the surface pores of said surface and tenaciously held thereon. 75

3. A valve seat for gas governors and the like, which is impervious to the passage of gases, comprising a leather base and a fibrous sheet securely bound on the surface of the leather by means of an organic binder, the fibrous sheet and the organic binder co-operating to render the leather gas-impermeable. 80

4. A valve seat for gas governors and the like, which is impervious to the passage of gases, comprising a leather base and a fibrous sheet securely bound on the surface of the leather by means of cellulose esters, the fibrous sheet and the cellulose ester co-operating to render the leather gas-impermeable. 85
